EXPULSION FUSE

Filed July 22, 1929

UNITED STATES PATENT OFFICE

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF DELAWARE

EXPULSION FUSE

Application filed July 22, 1929. Serial No. 379,929.

This invention relates to certain new and useful improvements in expulsion fuses and has as one of its objects the provision of a fuse structure in which all live parts thereof are confined within the enclosing box or housing to prevent accidental contact therewith on the part of the operator, and at the same time insure the thorough venting of the gases, occurring upon volatilization of the fuse, outside of the box.

Another object of this invention resides in the provision of an extension member secured to the discharge end of the fuse structure and having an opening through which one end of the fuse element passes to be connected with the lower fuse contact and which serves to conduct gases generated upon rupture of the fuse exteriorly of the housing.

And a further object of this invention resides in the provision of an abrupt increase in the passage formed by the combined internal diameters of the fuse tube and the extension member and through which the gases generated upon rupture of the fuse element are expelled, and the positioning of the opening in the extension through which the fuse element passes directly outward of said increase in the passage, which places the opening out of the path of the expelled gases and prevents their discharge through the opening into the housing interior.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated two complete examples of the physical embodiment of my invention constructed according to the best modes I have so far devised for the practical application of the principles thereof, and in which:

Figure 1 is a view partly in section and partly in side elevation of an expulsion fuse unit embodying my invention; and

Figure 2 is a fragmentary view partly in section and partly in side elevation of the lower end of the fuse tube illustrating a modified form of my invention.

Referring now more particularly to the accompanying drawings, the numeral 5 designates a box or housing preferably formed of porcelain or other material having insulating qualities and which is of substantial rectangular shape having its open front face closed by a door 6 also of insulating material. The door 6 is attached, as at 7, to a hinge member 8 fixed by mounting bolts or other means 9, to the bottom 10 of the housing, and covers an opening 11 in the bottom 10, leading from the interior fuse compartment 12 of the housing. The door 6 is of a size and shape to conform with the open front of the housing and when closed rests against a flange or bead 13 formed therein as illustrated in Figure 1 to provide a substantially tight closure.

The rear wall 14 of the housing is preferably provided with an external enlargement 15 to which a mounting bracket 16 is secured, and the side walls 17 of the housing are provided with apertures, not shown, registering with line terminal members 18 suitably mounted within the interior of the housing as at 19 and in electrical engagement with spring contact clips 20 between which the fuse member proper, indicated generally as at 21, is adapted to be received to electrically bridge the lines, not shown, connected with the terminal members 18.

The fuse member proper consists of an elongated tube 22 of insulating material having upper and lower contact members 23 and 24 mounted at the upper end of the tube and at a point spaced from its lower end, respectively. A fuse element 25 passed through the tube 22 and electrically bridges the contact members by having its upper end electrically connected with the contact member 23 and its lower end portion passed outwardly of the tube and up along its part 26 extended beyond the contact member 24 to be electrically connected therewith in any suitable manner, or as illustrated in my copending application, Serial No. 173,557.

As is customary in structures of this type, the contact members of the fuse are engaged with the spring clips 20 which are thus electrically bridged through the element 25, and in the present instance the lower end of the tube 22 terminates at a point spaced inwardly from the bottom wall 10 of the housing thus positioning the extended end portion of the fuse element entirely within the housing and protecting the operator against accidental contact with any of the live parts. This protection against exposure of live parts is a highly desirable feature in an expulsion fuse, but heretofore has never been accomplished without sacrificing the complete venting of the tube exteriorly of the housing. The present invention obtains the desired protection without in anywise impairing the efficiency of the device in the following manner.

An extension sleeve or tube member 27 is secured to the extreme lower end of the tube 22 to extend through the opening 11 to a point exteriorly of the housing, the tube having an opening 28 juxtapose the extreme lower end of the tube 22 through which the fuse element 25 passes to be connected with the contact member 24. The sleeve or extension 27 in the present instance has a bore of less diameter than the external diameter of the lower end portion 26 of the tube and its upper end is counter-board to a diameter to receive the lower end of the tube, the shoulder 29 at the bottom of the counter-bore limiting the telescopic movement of the extension onto the tube to which it is secured in any desired manner.

In Figure 2 a slightly modified construction of extension member 27 is illustrated in which the opening 28 is in the form of a slot extending from the upper end of the extension member or sleeve. This construction facilitates the securing of the sleeve to the lower end of the tube extension 26 after the fuse element has been secured within the tube.

From the foregoing description, taken in connection with the accompanying drawings, it will be readily apparent to those skilled in the art to which an invention of the character described appertains, that all live parts of the structure are entirely confined within and protected by the housing or box and at the same time the gases occurring upon volatilization of the fuse element are thoroughly vented exteriorly of the box.

It will also be noted that the opening 28 through which the fuse element is passed is positioned directly outward of the end of the tube 26 and as the extension member 27 has a larger internal diameter than the tube, the opening is out of the path of the expelled gases whose velocity, being high, prevents a diversion of the gases through the opening into the interior of the housing.

The larger external diameter of the exten-

sion member also more nearly closes the opening 11 and thus further prevents gases from entering the housing.

What I claim as my invention is:

1. A fuse member, comprising a tube, contact members mounted on the tube, a fuse element having one end electrically connected with the upper contact member and its other end passed through the tube outwardly of its lower end and directed upwardly to be electrically connected with the lower contact member exteriorly of the tube, and an open ended extension member secured to the lower end of the tube and providing a continuation thereof, said extension member having an opening therein juxtapose the lower end of the tube through which the fuse element passes.

2. A fuse member, comprising a tube, contact members mounted on the tube, a fuse element having one end electrically connected with one contact member and its other end passed through the tube outwardly of its lower end and bent upwardly to be electrically connected with the second contact member exteriorly of the tube, an open ended extension member of greater external diameter than the tube and rigidly secured to its lower end to form a continuation thereof, and said extension member having an opening therein juxtapose the lower end of the tube through which the fuse element passes.

3. In a fuse construction, the combination with a housing member having a front open face and a recessed bottom wall, a closure for the open face of the housing member and switch terminal members secured within the housing interior in alignment with the opening in the bottom wall, of a fuse member adapted to be mounted within the housing member by the switch terminal members to electrically bridge the same and including an insulating tube, a pair of terminal engaging contact members, means mounting one terminal engaging contact member on the upper end portion of the tube, means mounting the other terminal engaging contact member on the tube inwardly of its lower end, a fuse element having one end electrically connected with the upper terminal engaging contact member and being passed through the tube outwardly of its lower end and up along the exterior thereof, means electrically connecting the fuse element with the lower terminal engaging contact member, the lower end of the tube and the fuse element carried thereby being in line with the opening in the housing member bottom wall but spaced inwardly therefrom to prevent accidental contact therewith from the housing member exterior, and an open ended extension member carried by the tube and extending through the opening in the housing member bottom wall, the bore of said extension member forming a continuation of the tube bore and the fuse element

passing through an opening in the wall of the extension member inwardly of the bottom wall of the housing member.

4. In a device of the character described, 5 a normally closed housing having an opening in one wall, a fuse tube mounted within the housing with one end communicated with the exterior of the housing through said opening, contact members on the tube, terminal members mounted within the housing and adapted to receive the contact members, and a fuse element within the tube having one end electrically connected with one contact member and its other end passed outwardly 10 of the tube at a point inside the wall having the opening and directed along its exterior to be electrically connected with the other contact member, whereby said fuse element is entirely within the housing to prevent accidental contact therewith from the housing exterior.

5. In a device of the character described, the combination with a normally closed housing having line terminals therein, of a fuse 25 electrically bridging the terminals and comprising a tube, contact members engageable with the line terminals, a fuse element within the tube having one end connected with one contact member and its other end passed outwardly of one end of the tube and connected with the other contact member exteriorly of the tube, and a bored extension member carried by said end of the tube and projected through an opening in one wall of the housing 35 at all times communicating the tube interior with the exterior of the housing and having an opening adjacent the end of the tube through which the fuse element passes, the diameter of the extension member bore 40 being greater than that of the tube to provide an abrupt enlargement of the passage formed by the tube and extension member through which gases generated upon volatilization of the fuse element are expelled, said 45 enlargement being positioned adjacent the opening through which the fuse element passes to prevent gases passing through the opening and into the housing interior.

6. A fuse of the character described, comprising a tubular enclosing member having its internal diameter abruptly increased adjacent its discharge end and having an opening in its wall communicating with its portion of increased internal diameter, contacts 55 associated with the enclosing member, and a fuse element having one end connected with one contact member and its other end passed outwardly through said opening of the enclosing member and directed along the outside of the enclosing member to be connected with the other contact, whereby the velocity and path of gases expelled upon volatilization 60 of the fuse at the time they pass the opening through which the fuse element passes is such

as to preclude discharge of gases through said opening.

7. In a device of the character described, the combination with a housing having spaced line terminals therein, of a fuse electrically bridging the line terminals and comprising a tube, contacts engageable with the line terminals, a fuse element having one end connected with one contact and its other end passed outwardly of one end of the tube and bent back along its exterior to be connected with the other contact, the tube being of such length that it and the fuse element are entirely confined within the housing, and a bored member extended from the tube and having an opening through which the fuse element passes and projecting through an opening in one wall of the housing to conduct gases generated upon rupture of the fuse exteriorly of the housing, the diameter of the member bore being larger than that of the tube to provide an abrupt increase in the size of the passage through which the gases are expelled directly adjacent the opening through which the fuse element passes which prevents gases from being discharged through said opening into the interior of the housing.

8. In a device of the character described, the combination of the housing having spaced line terminals therein, of a fuse bridging the terminals and comprising a tubular enclosing member having its internal diameter abruptly increased adjacent its discharge end, contacts engageable with the line terminals, and a fuse element having one end connected with one contact and its other end passed outwardly through an aperture in the portion of the enclosing member having the increased internal diameter and extended along the exterior of the enclosing member to be connected with the other contact, the aperture in the enclosing member being disposed within the housing whereby all live parts are confined within the housing and that portion 100 of the enclosing member having an increased internal diameter projecting through an opening in said wall of the housing to conduct gases generated upon rupture of the fuse exteriorly of the housing, said aperture 105 being located out of the path of expelled gases precluding their discharge through the aperture into the housing interior.

In testimony whereof I have hereunto affixed my signature.

ALWIN G. STEINMAYER.
